METHOD OF DISTILLATION OF TAR

John Morris Weiss, New York, N. Y., assignor,
by mesne assignments, to The Barrett Com-
pany, New York, N. Y., a corporation of New
Jersey

Application September 30, 1926, Serial No. 138,582
Renewed November 8, 1930

3 Claims. (Cl. 196—76)

This invention relates to improvements in the process of distilling tar, especially tar obtained by the destructive distillation of coal or the pyro-genetic decompositon of petroleum oils. One object of the invention is to carry on the distillation in a smooth, even fashion and avoid the deposition of carbon on the shell of the still. Another object is to increase the distillate yield from a tar to a certain melting point pitch. A further object is to obtain higher melting point pitches than can be obtained in the ordinary methods of distillation. In addition there are other features of the invention, for example, a more convenient method of light oil recovery which will be evident as the description proceeds.

The term "tar" as used in this specification is intended to include all varieties of coal tar, carburetted water gas tar, oil gas tar, blast furnace tar, lignite tar, etc. In the distillation of these tars, the greater the formation of "free carbon", the less the yield of distillate oil and the greater the residual pitch. As oil has a higher market value than pitch, it is advantageous to produce as high a yield of oil as possible. For this reason vacuum distillation has been used with good effect but applying this to the ordinary tar still involves constructional changes to safeguard against external pressures at high temperatures and the degree of vacuum necessary for best results is difficult, if not impossible, to maintain in practical operations. When the tar temperatures reach a certain point it is impossible to maintain a high vacuum owing to the evolution of uncondensable gases from the decompositon of the tar, unless a pump of such over capacity is used as to render the installation uneconomical.

In my United States Patent No. 1,418,893 filed February 7, 1920 and issued June 6, 1922, I disclosed the facts that air normally used for agitating the tar during distillation tended to decrease the oil yield and that by the use of a gas chemically inert to the tar as an agitating means during the distillation and by using the gas in sufficient amount to appreciably lower the vapor pressure of the oils distilling, that the distillation could be accomplished at lower temperatures, with less cracking and therefore materially higher yields of oil than in the prior batch still processes. As the amount of oil carried by the gas was considerable, even past the condensing system, especially the lighter oils which are quite valuable, it was necessary to employ a cyclic system, returning the exit gas from the condenser to the still and thereby avoiding loss of oil vapors. As

a natural result the light oils were partly condensed with the heavy oils and would have required a redistillation of the heavier oils if it were necessary to completely separate them.

I have now discovered a way in which this disadvantage can be obviated, when the geographical location of the tar distillation plant is favorable and these light oils recovered without redistilling the heavier oils or put to useful work without recovery as such. Coal tar is produced at gas works and by-product coke oven plants and gas is always obtained along with the tar in the carbonization of coal. In the gas works the gas is used for domestic heating and illuminating purposes and is usually mixed with water gas which is carburetted by cracking petroleum oil and thereby adding to the water gas hydrocarbons of high calorific value thereby raising it to the standard set by the particular regulatory body under whose jurisdiction the gas company is operating. In the coke oven plants, the gas is usually used for fuel purposes within the plant but before being so used for fuel it is scrubbed with a suitable oil to recover its content of benzol and other low boiling hydrocarbons.

In the present invention I take gas after the tar has been separated from it but not necessarily further purified and pass it through the tar still during distillation to provide agitation and reduce the vapor pressures and thereby the distilling temperature of the tar vapors to the desired extent. The distillate is condensed and the gas separates from the condensed liquid naturally carrying some of the tar light oils in uncondensed form. This gas is then allowed to return to the main gas make of the plant. In the case of the gas works these added light oils will serve as a valuable enriching agent and enable the plant to use less carburettion on their water gas set, thereby saving both material and fuel. In the coke oven plant or other plant with similar facilities, the gas goes to oil scrubbers where the tar light oil would be removed along with the other light oil in the gas, in this way being obtained in a suitable form for refining and at a convenient point from the standpoint of operation. As the tar light oil is of the same general nature as the light oil in the gas, there is no interference with routine scrubbing practice or the subsequent refining operations.

As illustrative of how the process can be applied to tar distillation, reference may be made to the appended drawing which is purely diagrammatic but it must be understood that I

do not limit myself to any particular form of apparatus and the one shown is for illustrative purposes only.

In the drawing reference Figure I represents a still heated by any suitable means. The still I is provided with a drawoff II, a filling line and vent III. It is also provided with a pipe IV to remove the vapors of distillation to a condenser V which in turn delivers to a receiver VI 10 provided with a drawoff VII, a vent VIII and an outlet pipe IX. This line delivers into a main gas line of the plant X. Gas may be drawn from this main or another suitable gas source through the pipe XI and is forced by the pump 15 XII through the gas preheater XIII and by the pipe XIV to the bottom of the interior of the still through the perforated pipe XV. Arrows are used to indicate the direction of gas flow.

The still is charged with the tar to be distilled, the system closed and heat applied. Gas is passed through the still at the desired rate either with or without preheating. Distillation starts and is continued with gas passage until the residue in the still is of the desired consistency, 25 the volatile products being carried off from the still with the gas and for the most part being condensed in the condenser V and collected in the receiver VI. The gas still holding some portion of the tar oils leaves the receiver by the pipe IX and is returned to the gas line of the plant and, for example, in a coke oven operation, goes to oil scrubbers where the tar vapors so carried are recovered along with the light oils normally in the gas. When the distillation 30 is finished, heat and gas passage are discontinued and the residue removed from the still.

I prefer to pass an amount of gas not less than 1 cu. ft. (at ordinary atmospheric pressures and temperatures) and not more than 20 cu. ft. 40 per minute per 100 gallons of tar originally charged in the still. Preheating the gas passed is desirable but not necessary. I consider my process independent of the size or type of still used, the type of setting, the method of heating, the type of or means of cooling the condenser, 45 the means used for moving the gas, etc.

The yields of oil by my process will in the case of coke oven coal tars, when distilled to pitches of a melting point of around 300° F.,

be from 10 to 18% higher than when the same tars are distilled without gas passage. A further advantage of the process over ordinary batch still operation is that the residue may be run to a much higher melting point without endangering the apparatus or coking the charge and pitches of a melting point above 300° F. up to at least 450° F. can be obtained when this process is used without difficulty or undue coke formation on the shell of the still. The light oil in the gas is recovered if so desired or may be left there to increase its enriching power.

In the claims where the term "fuel gas" is used, I intend to include coal gas, water gas, oil gas and the like.

Having thus described my invention I claim:

1. The process of distilling tar with the aid of fuel gases, which comprises diverting part of a main stream of fuel gases, passing the gases so diverted through hot tar contained in a still to promote distillation of the tar, cooling the resulting gases and vapors to condense oils therefrom, and returning the gases and uncondensed tar vapors thus cooled to the main stream of the fuel gases subsequent to the point from which the gases were diverted.

2. The improvement in the process of claim 1, in which the fuel gases are tar laden gases and which are freed of their tar before introducing them into the still, and in which the main stream 105 of fuel gases, together with the gases employed for tar distillation, after re-combination, are passed to an absorbing system to recover light oils therefrom.

3. The process of distilling tar with the aid 110 of fuel gases, which comprises generating fuel gases containing tar constituents, cooling the gases and separating condensable constituents therefrom, dividing the gases into two streams, passing one stream through hot tar contained 115 in a still to promote distillation thereof, cooling the resulting gases and vapors to condense oils therefrom, returning the gases and uncondensed vapors, after such cooling, to the other portion of the gases, and passing the combined 120 gas streams to an absorption system for recovery of light oil therefrom.
